US00D964001S

(12) United States Design Patent (10) Patent No.: US D964,001 S
(45) Date of Patent: * Sep. 20, 2022

(54) UPPER FOR A SHOE

(71) Applicant: Columbia Insurance Company,
Omaha, NE (US)

(72) Inventor: Thomas McClaskie, Bethlehem, PA
(US)

() Term: 15 Years

(21) Appl. No.: 29/760,552

(22) Filed: Dec. 2, 2020

(51) LOC (13) Cl. 02-04

(52) U.S. Cl.

USPC D2/917

CLAIM

The ornamental design for an upper for a shoe, as shown and described.

DESCRIPTION

FIG. 1 is a perspective view of an upper for a shoe in accordance with my new design;

FIG. 2 is a top view thereof;

FIG. 3 is a left side view thereof;

FIG. 4 is a right side view thereof;

FIG. 5 is a front view thereof; and,

FIG. 6 is a back view thereof.

The broken lines, and any unshaded regions therein, show environmental structure that forms no part of the claimed design.
